UNITED STATES PATENT OFFICE.

ALFRED ROESCH, OF BRIDGEPORT, CONNECTICUT, ASSIGNOR TO THE DAVIS & ROESCH TEMPERATURE CONTROLLING COMPANY, OF NEW JERSEY.

DIAPHRAGM-CHAMBER.

SPECIFICATION forming part of Letters Patent No. 602,108, dated April 12, 1898.

Application filed November 23, 1897. Serial No. 659,566. (No model.)

To all whom it may concern:

Be it known that I, ALFRED ROESCH, a citizen of the United States, residing at Bridgeport, in the county of Fairfield and State of Connecticut, have invented a new and useful 5 Improvement in Diaphragm - Chambers, of which the following is a specification.

My invention relates to improvements in the construction of that class of diaphragm-chambers which are employed with compressed air or other fluid under pressure for actuating fluid-controlling valves.

My improvement pertains more especially, first, to the device employed for securing the 15 diaphragm and walls of the diaphragm-chamber together, and, second, to the device employed for closing the fluid-controlling valve by hand independently of the action of the diaphragm when the pressure in the dia- 20 phragm-chamber is removed.

The construction of my device is explained by reference to the accompanying drawings, in which—

Figure 1 represents a vertical section of 25 the diaphragm-chamber in connection with the fluid-controlling valve mechanism. Fig. 2 is a detail showing a top view of the screw by which the diaphragm-retaining disk is secured in place. Fig. 3 is a detail showing a 30 top view of the lever by which the fluid-controlling valve is closed when the diaphragm is relieved from pressure.

Like parts are referred to by the same reference-letters in the several views.

As heretofore constructed it has been common to secure the upper wall A of the chamber to an annular seat B against the diaphragm C by a series of bolts or screws or by threading the peripheries of the wall and seat. 35 By my improvement I am enabled to dispense with the bolts or screws heretofore used and also to dispense with the threads in the periphery of the wall of the chamber and seat, whereby the construction is simplified and 40 the cost of manufacture reduced.

As shown in Fig. 1, the inclosing wall A is secured to the seat B by pins D. The diaphragm C being in place, it is thus secured by the concavo-convex disk E, which disk 45 bears against the periphery of the diaphragm

C and holds it firmly against its seat B, thus forming an air-tight chamber between the diaphragm C and said disk E. The disk E is forced downward against the diaphragm, as stated, by a single central screw F, which 55 screw has screw-threaded bearings G in the wall A and bears at its lower end against the upper wall of said disk E, whereby as said screw G is turned downward against said disk the same is forced firmly against the periphery of said diaphragm, as stated, thus forming a close joint.

The object of the inclosing wall or cap A is to serve simply as a supporting-bearing for the central fastening-screw F, in connection 65 with the diaphragm C. It is obvious, however, that said fastening-screw may be thus supported in connection with the seat by an open bracket or spider instead of an unbroken continuous wall, as shown. Air or other fluid 70 under pressure is led to the space between said disk E and the diaphragm through the central duct H, whereby said diaphragm is forced downward and the fluid-controlling valve I is closed, motion being communicated 75 from said diaphragm through the diaphragm-bearing plate A' and the valve-stem J. When said chamber is released from pressure, the diaphragm C is thrown upward and said fluid-controlling valve is opened by the recoil of 80 the spiral spring K.

The central screw F is provided with a recess L for the reception of a wrench, by which it is turned and adjusted in its bearings against the disk E. To provide for closing 85 the valve I against its seat M, as may sometimes be desired, when said diaphragm-chamber is relieved from pressure, I have employed a valve-actuating lever N, which is fulcrumed to a stationary bracket O upon the pivotal 90 bolt P and is connected at its inner end to the valve-stem J between the diaphragm-bearing plate A' and the collar or flange Q, whereby as the outer end of the arm N is raised said valve is forced downward to its 95 seat and closed. The outer end of the lever N is connected with the stationary arm R by the hand adjusting-screw S, which screw S has threaded bearings in said arm R, while its lower end passes through a loosely-fitting 100

aperture B' in said lever N, whereby as said screw is turned upward it carries with it the outward end of said lever N, thereby causing the inner end of said lever to be thrown downward, carrying with it said valve-stem and valve, whereby said fluid-valve is closed and retained in its closed position, as stated, independently of the action of said diaphragm. The bracket O may, if desired, be cast integral with the seat or wall of the diaphragm-chamber; but for convenience of construction I have shown it formed in a separate piece, which is clamped to the periphery of the diaphragm-chamber by the clamping-arm T and binding-screw U. The lever N may be connected to said valve-stem in any desired manner, but by the preferred form shown its inner end is bifurcated in shape, and the respective forks C' C' of the lever engage against the upper surface of the bearing-flange Q upon the respective sides of the stem J, as shown in Fig. 1.

The lower end of the hand-screw S is provided with an operating-knob V, which bears at its upper surface against the under side of the lever N as it is turned, thus communicating the required movement to said lever when desirous to close the valve.

All that part of the device below the valve-seat B, by which such seat is connected with and supported from the valve-chamber D', consisting of the supporting-arms E' E', stuffing-nut F', and the central part G', are of the ordinary construction and well known to those skilled in the art to which the invention pertains.

Having thus described my invention, what I claim as new, and desire to secure by Letters Patent, is—

1. In a diaphragm-chamber, the combination with an annular diaphragm-seat and diaphragm; of an interior wall or disk adapted to impinge upon the periphery of said diaphragm, above its seat; an exterior inclosing wall located above said disk, secured at intervals to said annular seat; and a central binding-screw having screw-threaded bearings in said exterior wall and adapted, as it is turned downward, to bear against said interior wall or disk, whereby the latter is retained in close contact with said diaphragm, substantially as and for the purpose specified.

2. In a diaphragm-chamber, the combination with an annular diaphragm-seat B and diaphragm C; of an interior wall or disk E, adapted to impinge upon the periphery of said diaphragm above its seat; an exterior inclosing wall A located above said disk E; two or more fastening-pins D located at intervals in the contiguous bearings of said exterior wall A and said diaphragm-seat B, by which said

parts are secured together; and a central bearing-screw F having screw-threaded bearings G in said exterior wall, and adapted, as it is turned downward, to bear against said interior wall or disk E, whereby the latter is retained in close contact with said diaphragm, said diaphragm is forced firmly to its seat, and an air-tight chamber is formed between said diaphragm and said inclosing disk E, substantially as and for the purpose specified. 65

3. In that class of diaphragm-chambers in which the diaphragms are actuated by compressed air for operating fluid-controlling valves, the device herein described for actuating the fluid-controlling valve independently of the action of said diaphragm, when the same is relieved from pressure, consisting in the combination with a diaphragm-chamber and the stem of a fluid-controlling valve of an actuating-lever centrally pivoted to a supporting-bracket and connected at one end with the valve-stem of said fluid-controlling valve, and at its opposite end, by an adjusting-screw, with the screw-threaded bearings of a stationary supporting-arm, whereby, as said screw is turned forward in its bearings, said lever is swung upon its pivotal support, and said fluid-controlling valve is forced to its seat, substantially as and for the purpose specified. 70

4. In that class of diaphragm-chambers in which the diaphragms are actuated by compressed air for operating fluid-controlling valves, the device herein described for actuating the fluid-controlling valve independently of the action of said diaphragm, when the same is relieved from pressure, consisting in the combination with a diaphragm-chamber and the stem of a fluid-controlling valve of an actuating-lever; a lever-supporting bracket adjustably attached to said diaphragm-chamber; and an adjusting-screw having screw-threaded bearings in a projecting arm of said bracket, said lever being centrally pivoted to said supporting-bracket and connected at one end with the valve-stem of said fluid-controlling valve, and at its opposite end by said adjusting-screw, with the screw-threaded bearings of a projecting arm from said bracket, whereby, as said screw is turned forward in its bearings, said lever is swung upon its pivotal support, and said fluid-controlling valve is forced to its seat, substantially as and for the purpose specified. 85 90 95

In testimony whereof I have signed my name to this specification in the presence of two subscribing witnesses.

ALFRED ROESCH.
